United States Patent Office

Des. 229,704

Patented Dec. 25, 1973

229,704

PUPPET

Russell B. Odell, Elgin, Ill., assignor to David C. Cook Publishing Company, Elgin, Ill.

Filed Sept. 11, 1972, Ser. No. 288,139

Term of patent 3½ years

Int. Cl. D21—01

U.S. Cl. D34—2 R

FIG. 1 is a front elevational view of a puppet embodying my new design;

FIG. 2 is a rear elevational view;

FIG. 3 is a side elevational view as seen from the left-hand side in FIG. 1;

FIG. 4 is a top plan view; and

FIG. 5 is a bottom plan view.

I claim:

The ornamental design for a puppet, substantially as shown and described.
